UNITED STATES PATENT OFFICE.

MARGARET STONEBRIDGE, OF GARRISON, NEW YORK.

DESIGN FOR A MASSAGE-BRUSH.

SPECIFICATION forming part of Design No. 34,439, dated April 30, 1901.

Application filed March 28, 1901. Serial No. 53,355. Term of patent 14 years.

To all whom it may concern:

Be it known that I, MARGARET STONEBRIDGE, a citizen of the United States, residing at Garrison, in the county of Putnam and 5 State of New York, have invented and produced a certain new and original Design for Massage-Brushes, of which the following is a full, clear, and exact specification.

My design relates to massage-brushes; and 10 its object is to produce a conveniently-handled and attractive form of brush.

The design will be more particularly described with reference to the accompanying drawing, in which the figure represents a 15 perspective view of the brush.

The leading features of the design are the raised intersecting ridges a, with the intervening depressions b, all mounted on the body portion c.

Having thus described and illustrated my 20 invention, I claim—

The design for a massage-brush herein described and illustrated.

In testimony whereof I affix my signature in presence of two witnesses.

MARGARET STONEBRIDGE.
